DOORLATCH

William A. Gram, Wainfleet Township,
Welland County, Ontario, Canada

Application May 6, 1935, Serial No. 20,000

10 Claims. (Cl. 292—210)

My invention relates to improvements in door latches, and an object of my invention is to devise a latch, particularly adapted for use on the doors of motor vehicles and aircraft, having 5 a substantially hook-shaped latch element adapted to surround a keeper element on the door jamb so that accidental opening of the door due to vibration is impossible.

Another object is to provide a latch which will 10 permit the door to be held shut securely even when it is prevented from completely abutting the jamb, such as by warping of the door or by the presence of obstructions between the door and jamb.

15 A still further object is to devise a latch which will be particularly rugged and which it will be substantially impossible to force apart when locked.

Yet another object is to provide a latch having 20 pneumatic means for ensuring gentle closing of the door and preventing slamming.

An additional object is to provide means for locking my latch in the door latching position by freeing the latch mechanism from the latch 25 operating means so that the latch cannot be forced by attacking such means.

Yet another object is to devise a latch including means whereby operation of the latch operating means will open the door through the latching position without any pull on the door being required.

With these and other objects in view which will hereinafter appear as the specification proceeds my invention consists, in its preferred embodiment, of the construction and arrangement 35 all as hereinafter more particularly described and illustrated with reference to the accompanying drawing, in which:

Fig. 1 is a fragmentary elevational view of a 40 door and door-jamb showing my latch installed thereon and with part of the latch casing broken away to reveal the latch mechanism;

Fig. 2 is a longitudinal sectional view thereof 45 taken along the line 2—2 of Fig. 1, showing in broken lines the positions the latch elements assume when the door is open;

Fig. 3 is a transverse sectional view taken along the line 3—3 of Fig. 2; and

Fig. 4 is a fragmentary elevational view of the 50 door jamb showing the latch keeper installed thereon.

Like characters of reference refer to corresponding parts in the different views.

Referring to the drawing, my improved latch 55 mechanism may be contained in a casing I set

into a door 2 adjacent a jamb 3 having a stop 4 on which is secured a slotted keeper plate 5 across the free ends of which a latch keeper 6 is secured.

A substantially cylindrical latch element 7 rotatably positioned on a pin 8 secured in the latch casing I has a latch keeper engaging notch 9 in its periphery and a stop pin 10 projecting from one face. The latch element is actuated by a rod 11 pivotally secured at one end by a pin 12 in a recess in the periphery of the latch element at a point approximately diametrically opposite the notch 9, the opposite end of the rod 11 passing freely through an orifice 13 in the latch casing and terminating in a piston 14, adapted to reciprocate in a dash-pot cylinder 15 and carrying a sealing washer 16. A spring 17 around the rod 11 is compressed between a stop 18 on the rod and one end of the latch casing I.

The latch element 7 is held in the door latching position by a rod 19 pivotally connected at one end to the stop 18 on the rod 11 and having a toothed dog 20 on its free end which is adapted to engage a toothed rack 21 secured to the latch casing I. A spring 19' serves to urge the free end of the rod 19 against the rack 21.

A latch operating shaft 22 is journaled in an orifice in the casing I being secured therein by the shoulders 23, and has an operating handle 24 thereon. Such shaft projects into the bore of 30 a hollow shaft 25 which also passes through an orifice in the latch casing I and terminates in a second operating handle 26. A sleeve 27 around the shaft 22 carries a latch releasing member 28 adapted to engage the rod 19 along the edge 35 29 of the member, such member 28 being connected by a cable 30 to the stop 18 on the rod 11, a spring 31 connected at one extremity to a projection 32 on the member 28 and at the other to one end of the latch casing I serving to normally hold the member 28 against a stop 33 on the casing I.

Operative connection between the handles 24 and 26 and the latch releasing member 28 is effected by means of bosses 34 projecting from a flange 35 on the shaft 22 which are adapted to enter correspondingly shaped recesses 36 and 37 in integral flanges 38 and 39 on the hollow shaft 25 and the sleeve 27 respectively, a spring 40 around the shaft 25 compressed between the casing I and the flange 38 and a second spring 41 around the shaft 22 compressed between the casing I and the sleeve 27 serving to hold the flanges 38 and 39 in engagement with the flange 55

35. An orthodox cylinder lock 42 having a rotatable shaft 43 carrying a disc 44, the plane faces of which are at an angle to each other, is so positioned in the door 2 adjacent the shaft 22 that the periphery of the disc 44 projects between the flanges 38 and 39.

The operation of my latch is as follows: When the door is latched as shown in the full line positions of Figs. 1 to 3, the notch 9 of the latch element 7 engages the keeper 6, the former being held securely against rotation by the toothed dog 20 engaging the rack 21.

To release the latch for opening the door, either of the handles 24 and 26 are rotated in the direction to move the element 28 away from the stop 33 which it normally abuts. The first slight rotation of the element 28 permitted by the slack in the cable 30 lifts the dog 20 out of engagement with the rack 21, allowing movement of the rod 11. Further rotation of the element 28 then takes up the remaining slack in the cable 20 and pulls the rod 11 in a direction to further compress the spring 17 and rotate the latch element, such rotation causing one side of the notch 9 to bear against the outer surface of the keeper 6 to open the door slightly. When further rotation of the element 7 causes the pin 12 to cross a line joining the pin 8 and the centre of the orifice 13, the spring 17 causes the element 7 to rotate by a snap action until the stop pin 10 abuts the latch casing 1, imparting a further opening impulse to the door. With the latch mechanism in this position (indicated by the dotted lines in Fig. 2) the notch 9 is so directed that the keeper may pass out of the notch as the door is opened. Releasing the operating handle then restores the element 28 to its normal position by the action of the spring 31, allowing the dog 20 to re-engage the rack 22 to hold the rod 11 and connected latch element 7 against movement.

To latch the door either of the handles 24 and 26 are rotated sufficiently to free the dog from the rack, and the door is swung shut. After the keeper 6 enters the notch 9, further movement of the door towards the jamb revolves the latch element 7 until the pin 12 recrosses the line between the pin 8 and the orifice 13, whereafter the spring 17 causes the element 7 to rotate further, by a snap action, to force the door tightly against the jamb. It should be noted that once the pin 12 has crossed the line joining the pin 8 and the orifice 13, the spring 17 acts to keep the latch element 7 in engagement with the keeper 6, and the dog 20 engaging the rack 21 prevents reverse motion of the element 7 which would free the door for opening. During this final movement of the element 7, the piston 14, moving out of the cylinder 15 against the atmospheric pressure, retards the movement of the rod 11 and the element 7 to prevent slamming of the door, but without decreasing the closing force exerted by the spring 17.

To lock the latch, the lock 42 is actuated by its key, which causes the shaft 43 carrying the disc 44 to rotate from the normal unlocked position with the thin edge of the disc between the flanges 38 and 39, until the thick edge is between the flanges, thus forcing the flanges apart against the tension of the springs 40 and 41, until the bosses 34 on the flange 35 no longer engage the recesses 36 and 37 in the flanges 38 and 39 respectively. The handles 24 and 26 are then free to revolve without operating the latch. On unlocking the latch, it is only necessary to revolve either handle until a boss 34 enters the corre-

sponding recess, when operative connection between the handle and the latch releasing member 28 is reestablished.

An advantage of my improved latch is that since the latch element 7 substantially surrounds the keeper 6, the door is latched very securely, and the forcing of the door by means of an instrument inserted between the door and the jamb is precluded.

A further advantage is that the latching and unlatching of the door is positively effected by the snap action of the spring 13, so that any difficulty in closing and opening the door due to binding of the latter against the jamb is eliminated.

Yet another advantage of my construction is that it provides, by means of the dog mechanism, for positive latching of the door even if the latter is not tightly closed, and in addition the position of most complete closing reached is always maintained since the dog follows the closing motion of the latch but never permits reversal of such motion until released by the operating handle.

An additional advantage of my latch is that the pneumatic piston and cylinder ensures smooth and substantially noiseless latching of the door.

While I have described and illustrated one preferred form of my invention, it will be obvious that there are numerous other ways of embodying the principles of my device, so my disclosure is intended to impose no limitation on the scope of my invention beyond that set forth in the appended claims.

What I claim as my invention is:

1. A door latch, adapted to latch on a keeper pin positioned on the door jamb, comprising a rotatable latch element journaled in the door adjacent the edge thereof and having a radial slot adapted to receive the keeper pin during rotation of the latch element into the latching position as the door is closed, spring means for actuating the latch element alternatively into the door latching and the door opening positions, and releasable means for retaining the latch element in the position of greatest rotation attained during the latching of the door.

2. A door latch as claimed in claim 1 wherein means is provided for manually actuating the latch element against the action of the spring means from the door latching position to the position where the spring means acts to actuate the latch element into the door opening position.

3. A door latch as claimed in claim 1 wherein means is provided for manually actuating the latch element against the action of the spring means from the door latching position to the position where the spring means acts to actuate the latch element into the door opening position and means for locking the latch when in the door latching position comprising a releasable operative connection between the manual actuating means and the latch element.

4. A door latch as claimed in claim 1 wherein fluid operated means is provided for damping the spring action during latching of the door.

5. A door latch, adapted to latch on a keeper pin positioned on the door jamb, comprising, a rotatable latch element journaled in the door adjacent the edge thereof and having a radial slot adapted to receive the keeper pin during rotation of the latch element into the door latching position as the door is closed, a rod pivotally secured at one extremity to the periphery of the latch element at a point substantially di-

metrically opposite the slot therein, a bracket secured in the door and having an orifice therein adapted to freely receive the other extremity of said rod, a stop on said rod adjacent its pivotal connection with the latch element, a coil spring around said rod and compressed between said stop and said bracket, the bracket being so positioned that the point of connection of the rod with the latch element crosses a line joining the centre of the latch element and the centre of the orifice in the bracket as the latch element rotates between the door opening and the door latching positions, manually operable means for actuating the latch element against the action of the spring out of the door latching position, and means, releasable by the manually operable means, for retaining the latch element in the position of greatest rotation attained during the latching of the door.

6. A door latch as claimed in claim 5 wherein the manually operable means comprises a shaft journalled in the door, a handle on the shaft, a cam secured to the shaft and flexible means secured at one extremity to the cam and at the other extremity to the stop on the rod pivotally connected to the latch element, and the releasable means comprises a toothed rack positioned in the door, a rod pivotally secured at one extremity to the stop on the above first mentioned rod, teeth on the other extremity of said last mentioned rod adapted to engage the teeth in the rack, spring means for urging the toothed rod extremity into engagement with the rack, said cam being adapted to lift the toothed extremity of the rod out of engagement with the rack upon the initial actuation of the manually operable means during the unlatching of the door, means for limiting the movement of the cam between the door opening and door latching positions, and spring means for normally retaining the cam in the door latching position.

7. A door latch as claimed in claim 5 wherein

means is provided for damping the spring action of the latch mechanism comprising a cylinder secured to the bracket in the door in which the free end of the latch element actuating rod is adapted to reciprocate, a piston on the free end of said rod, and an obturating member on the piston.

8. A door latch as claimed in claim 5 wherein means is provided for locking the latch element when in the door latching position comprising a releasable operative connection between the manual actuating means and the latch element.

9. A latch mechanism as claimed in claim 10 wherein said wedge means comprises a member rotatably positioned adjacent said operating shaft, and a disc carried by said member having plane faces disposed at an angle to each other, said disc being adapted to be alternatively positioned with a portion of the periphery of lesser thickness between said flanges for actuation of the cam by the operating shaft, and with a portion of the periphery of greater thickness between said flanges for separation of the latter to free the cam from operative connection with the operating shaft for locking of the latch mechanism.

10. In a latch mechanism including a latch operating cam and a rotatable operating shaft therefor, locking means comprising a flange on the operating shaft, a boss on said flange, a sleeve to which the operating cam is secured surrounding a portion of said shaft, a flange on said sleeve adjacent the flange on the operating shaft and having a recess adapted to receive the boss on the shaft flange, spring means adapted to normally urge said flanges together for engagement of the boss in the recess for operatively connecting the operating shaft with the cam, and wedge means for separating said flanges to free the cam from operative connection with the operating shaft for locking of the latch mechanism.
